United States Patent

Des. 240,188
Patented June 8, 1976

240,188

COMBINED CAN AND BOTTLE OPENER

Robert R. Lytle, 1942 High St.,
Cuyahoga Falls, Ohio 44221

Filed Nov. 25, 1974, Ser. No. 526,749

Term of patent 14 years

Int. Cl. D7—99

U.S. Cl. D8—18

FIG. 1

FIG. 2

FIG. 3

FIG. 1 is a perspective view of a combined can and bottle opener showing my new design;

FIG. 2 is a side elevational view thereof; and

FIG. 3 is an end elevational view taken from the left of FIG. 2.

The rear side is identical in appearance to the side shown in FIG. 2.

I claim:

The ornamental design for a combined can and bottle opener, as shown and described.
